Primary Examiner — Paula Greene

CLAIM

The ornamental design for a module maintenance system-parallel cover, as shown and described.

DESCRIPTION

FIG. 1 is a top view of our module maintenance system-parallel cover showing our new design;

FIG. 2 is a right side view thereof;

FIG. 3 is a front view thereof;

FIG. 4 is a left side view thereof;

FIG. 5 is a bottom view thereof;

FIG. 6 is a top front view thereof; and,

FIG. 7 is a bottom rear view thereof.

The broken lines form no part of the claimed design.
